UNITED STATES PATENT OFFICE.

JOHN M. WASHBURN, OF ATTICA, INDIANA.

STAMP OR LABEL ATTACHING DEVICE.

SPECIFICATION forming part of Letters Patent No. 651,681, dated June 12, 1900.

Application filed October 13, 1899. Serial No. 733,479. (No model.)

To all whom it may concern:

Be it known that I, JOHN M. WASHBURN, a citizen of the United States, residing at Attica, in the county of Fountain and State of Indiana, have invented certain new and useful Improvements in Stamp or Label Attaching Devices; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in devices for attaching adhesive stamps, labels, &c., to envelopes and packages, in which means are provided for holding stamps or labels in a suitable receptacle, from which they may be taken out singly by reason of their gummed surfaces coming in contact with the previously-moistened surface of the envelope or package to which they are to be attached, a suitable moistening attachment being held adjacent to the stamp-containing receptacle.

More specifically, the present invention resides in the provision of a block which is recessed out to receive a stamp-receiving receptacle which supports a plunger and table on which the envelope is held while being stamped, said receptacle surrounding a stationary block to which the stamps are held.

Another feature of the invention consists in the provision of means for locking the stamp-receptacle either at its highest or lowest throw, whereby the machine may not be tampered with by strangers, and in the means for throwing back the shelf carrying the spring-actuated plunger.

My invention is clearly illustrated in the accompanying drawings, which, with the letters of reference marked thereon, form part of this application, and in which drawings—

Figure 1 is a vertical central section through my invention. Fig. 2 is a detail view showing the manner of adjustment whereby the shelf carrying the spring-actuated plunger is thrown back. Fig. 3 is a detail view showing the locking means for holding the stamp-receptacle in a fixed position, and Fig. 4 is a cross-sectional view on line 4-4 of Fig. 1.

Reference now being had to the details of the drawings by letter, A designates the base of the machine, which has a vertical portion B, which is hollow and in which the stamp-receptacle C is adapted to telescope. This stamp-receptacle has on one side a longitudinal slot C' with enlarged ends C², and D is a thumb-screw which is threaded and has a flattened portion D', which is adapted to slide in the longitudinal slot in the stamp-receptacle when said flattened portion is turned so that its parallel sides are in alinement with the walls of said slot; but when turned at right angles, which is possible to be done when the stamp-receptacle is at its highest or lowest limit, said receptacle will be held locked either at its highest or lowest limit, as will be readily understood.

Mounted upon a removable plate E, which is screwed or otherwise fastened to the bottom of the stamping-machine, is a post F, upon which the stamps in the receptacle rest, and secured to the inner walls of said telescoping receptacle C is a plate F', which has a central aperture through which said post passes, and bearing between the under surface of said plate F' and the upper surface of the plate to which said post is secured is a coiled spring G, provided to normally throw said telescoping receptacle to its highest limit. Said post F has its upper end flanged and is of a size equal to the opening in the telescoping receptacle. Mounted on the upper surface of the perforated plate F' is a buffer F², which has an aperture through which said post passes, which buffer is provided to deaden the noise when the telescoping stamp-receptacle carrying the same is thrown to its highest position after being depressed in the act of affixing a stamp, the upper face of the buffer coming in contact with the under surface of the flanged top of the stamp-supporting post, as clearly shown in the drawings. This buffer and the plate supporting it serve another function, which is to prevent the telescoping receptacle from being thrown out of the upright portion of the casing by the tension of the spring, said buffer contacting with the under surface of the flanged portion of the stamp-supporting post, thus limiting the upward throw of the receptacle. It will be noted that the base portion of the casing is

apertured, whereby the device may be securely fastened to a table, and is recessed out for a short distance in its bottom, so as to allow the under surface of the plate secured to the 5 stamp-supporting post to be above the lowest portion of the machine.

The table H, which is secured to the upper end of the stamp-receptacle, has an aperture H', leading through to the said stamp-receptacle, and adjacent to said opening is a fount K, in which is journaled a moistening-roller K', having about its circumference preferably a leather strap or some other hard material, and a short distance above said moistening-wheel is a plate L, secured to the vertical portion of the table, and fastened to the under surface of this plate is a spring M, the free end of which is held adjacent to said moistening-roller, and said spring is provided 15 to hold the letter or parcel to which the stamp or label is to be affixed in contact with the moistening-roller to lubricate the surface of the letter or parcel before the latter comes in position to receive the stamp or label.

25 Mounted on the ears N on the vertical portion of the table is the swinging shelf N', which has ears N², through which and the ears of said table passes the threaded screw Q, upon which a wing-nut Q' turns. This 30 screw has its opposite end bent upon itself and passes through registering apertures in one of the ears of the table and of the shelf in order to lock the shelf, so that it will be parallel with the upper surface of the table, 35 a slight space intervening. When it is desired to swing the table back, the said wing-nut is removed and the pin drawn out, and the shelf is readily allowed to be turned back. Mounted in a raised portion of said shelf is 40 a plunger R, having a stem R', to the upper end of which a knob T is secured, and interposed between the upper end of said raised portion and the knob and about the stem of the plunger is a coiled spring J, provided to 45 keep said plunger normally at its highest throw.

Secured to one end of the table is an L-shaped bracket-guide I, which is adapted to swing out, as shown in dotted lines in the 50 drawings, and is provided for the purpose of forming a stop, against which the envelop strikes when the stamp is to be affixed. In case two stamps are to be affixed to an envelop, after the first stamp is affixed said bracket is 55 swung out to the position indicated in dotted lines, so as to allow a second stamp to be affixed beside the first one.

In operation the stamps or labels, with their adhesive surfaces upward, are placed in the 60 receptacle, and the letter or parcel to which the stamp or label is to be affixed is passed over the moistened roller, and when in proper position over the upper end of the stamp-receptacle the operator depresses the plunger, 65 which holds the envelop or parcel in position, and a further depression of the plunger, car-

rying with it the table, down to its lowest limit will forcibly affix the stamp against the moistened surface of the envelop or parcel, after which the latter is removed.

What I claim to be new, and desire to secure by Letters Patent, is—

1. A stamp and label affixer consisting of a base-block having a vertical hollow portion, a spring-actuated stamp-receiving receptacle 75 telescoping therein, a table integral with said receptacle, a moistening device carried thereon and a plunger carried by the table adapted to strike against the latter and depress the same, and a stationary post on which the 80 stamps rest.

2. A stamp or label affixer comprising a base having an upright portion, a spring-actuated telescoping hollow shaft comprising a stamp-receptacle telescoping in said upright 85 portion, a table integral with the upper end of said hollow shaft, a moistening device carried thereby, a hinged shelf and spring-actuated plunger carried thereby, a stationary 90 stamp-supporting post over which said shaft telescopes, as set forth.

3. A device for affixing adhesive stamps and labels to envelopes, &c., consisting of the base having an upright hollow portion, a spring-actuated shaft telescoping therein, 95 said shaft having an elongated slot with enlarged ends in its wall, a screw mounted in a threaded aperture in said upright portion and having a flattened portion adapted to slide in said slot and to be turned at right angles at 100 either end of said slot, whereby the shaft may be locked at its highest or lowest throw, as set forth.

4. In a device for affixing adhesive stamps to letters, &c., the base and hollow upright 105 portion, the hollow shaft telescoping in the latter, the integral table at right angles to said shaft at the upper end of the latter, the stationary stamp-supporting post, the apertured guide-plate secured to the inner walls 110 of said hollow shaft and surrounding said post, the detachable plate secured to the base portion and carrying said stamp-supporting post, and the spring interposed between said guide and detachable plates, as set forth. 115

5. In combination with the spring-actuated shaft, the table integral with said shaft, said table having ears, the shelf carrying the plunger, the screw passing through registering apertures in said ears, one end of said screw being bent upon itself and passing through registering apertures in two of the ears adjacent to each other and a wing-nut holding said screw in its locked relation, as set forth. 120

6. In combination with a device for affixing adhesive stamps and labels to envelopes, &c., having the table and the mechanism described, the pivoted stop mounted on said table, as set forth. 125

7. In a device for affixing adhesive stamps to letters the combination with the base portion having an upright hollow projection, of

a shaft telescoping therein; a table integral with the upper end of said shaft, said table having a vertical plunger-carrying portion and means coacting with said plunger for placing a stamp upon an envelop; the fount and moistening-roller turning therein, the plate secured to said vertical portion, a spring secured to the under surface of said plate, the

free end of the spring being held adjacent to the moistening-roller, as shown and described.

In testimony whereof I affix my signature in presence of two witnesses.

JOHN M. WASHBURN.
